UNITED STATES PATENT OFFICE.

ROBERT J. ADAMS, OF WEST AUBURN, MASSACHUSETTS.

DEVICE FOR REMOVING BROKEN PICKS.

1,371,659.

Specification of Letters Patent.

Patented Mar. 15, 1921.

Application filed May 6, 1920. Serial No. 379,385.

To all whom it may concern:

Be it known that I, ROBERT J. ADAMS, a citizen of the United States, residing at West Auburn, in the county of Worcester and State of Massachusetts, have invented a new and useful Device for Removing Broken Picks, of which the following is a specification.

This invention relates to a mechanism for removing broken filling threads from the open shed formed by the warp of a loom, and the principal objects thereof are to provide an efficient and practical means for accomplishing this result and more specifically 10 to provide for moving the pick removing element so that it will follow up the shed and enter the space between the warp threads so as to engage and extract the broken filling thread even if it lies deep in the shed as is 15 apt to be the case. The invention also involves means whereby the device is readily adjustable across the loom so that it can be applied to the weaving of cloth of different widths on the same loom and effective means 20 for guiding the device and also for securing this adjustment. The invention also involves other improvements in details of construction and combinations of parts as will appear.

30 Reference is to be had to the accompanying drawings, in which—

Figure 1 is a front view of a part of the lay of a loom with a preferred embodiment of this invention applied thereto;

35 Fig. 2 is a transverse sectional view of the same showing the operating connections;

Fig. 3 is a sectional view on the line 3—3 of Fig. 4 and on enlarged scale showing the pick remover of the opposite side of the 40 loom, from that shown in Fig. 1;

Fig. 4 is a plan of the same;

Fig. 5 is an end view thereof;

Fig. 6 is a view similar to Fig. 3 but with the parts in their operative instead of their 45 normal position;

Fig. 7 is a plan of the same with parts in section, and

Fig. 8 is an end view with the parts in the same position.

50 I have shown the invention as applied to the lay 10 of an ordinary loom by means of three or more brackets 11 secured on the back of the lay and having extensions projecting to the front thereof for supporting 55 a pair of tracks 12 arranged in a vertical

plane and constituting a guide. These tracks may, and preferably do, extend all the way across the loom on the lay but located below it as indicated, or if desired, there may be a separate pair of tracks on 60 each end as the central portion of these tracks would seldom or never be used. These tracks are employed to support and guide a slide 13 on each end of the loom. Each slide is provided with four headed rolls 14, two 65 above and two below the lower and upper edges of the two tracks respectively, so that these slides 13 are capable of being moved along the tracks.

On the back girt 20 of the loom are fixed 70 at proper distances from the two ends of the loom a pair of brackets 21. These brackets can be loosened and moved toward or from each other to provide for operation on cloth of different widths. Each bracket 75 has a pivot 22 to which is connected a lever 23 held up by a spring 24 connected with the back of the lay. Each lever has a roll 25 which runs on a cam 26 adjustably fixed to the bottom shaft 27 of the loom. If the 80 brackets 21 are adjusted the cams 26 will be adjusted accordingly, also the brackets 31 and cams 46.

At the end of the lever 23 is an adjustable rod 28 which is connected with a bell crank 85 29 pivoted on a stud 30 carried by a bracket 31 supported by the tracks 12. This bell crank is connected with a link 32 which is pivoted to the center of the slide 13.

On each rotation of the cam 26 the parts 90 remain in the positions shown in Figs. 1 to 5 inclusive until the two cams 26 turn to the position in which the rollers 25 enter depression 33 in these cams which they do alternately. Then the spring 24 raises the lever 95 23 and link 28 and swings the bell crank 29 in toward the center of the loom at the top. This results in moving one slide 13 inwardly and with it the mechanism which it carries.

On each of the slides 13 there is a hollow 100 standard 35 fixed thereto and having a passage through it for connection at 36 with a hose for the exhaust of air. This hollow standard which is shown in vertical position is provided with a narrow vertical slot 105 34 at its top for the admission of air from outside.

Oscillatably mounted thereon is a casing 37 which supports a duck-bill 38 which is formed of two parts, each provided with a 110

passage 39. The end of the duck-bill terminates in a slot 40 which, in the position shown in the first five figures, does not register with the slot 34 which therefore is closed. The two parts of the duck-bill 38 are held together by a cap 48.

Extending from the casing 37 is an arm 41 substantially in alinement with the duck-bill and provided with a roller 42 which enters a slot 43 in a lever 44 pivoted at 47 on the slide 13. This lever is provided with another roller 45 at its end which engages in a cam 46 adjustably fixed to the track 12. The cam 46 is adjusted to allow adjustment 10 of the parts for different widths of cloth, and also to control the throw of the duck-bill into the shed. All these parts, except the cams are self-contained. They are all carried by the track and can be mounted on it 15 as a whole.

Now when the slide 13 moves in accordance with the operation of the cam 26 toward the center of the loom the duck-bill is not only moved inwardly toward the center 25 and guided accurately by the track, but it is swung forwardly into the shed in the direction of the feed of the cloth by the action of the roller 45 in engaging the fixed cam 46 as shown in Figs. 6, 7 and 8. The duck-bill therefore moves up into the shed and substantially into contact with the crossing warps, so that wherever the broken filling 30 may lie some part of it will be in a position to be engaged by the duck-bill and sucked 35 into it by the air suction constantly exerted. As will appear from Fig. 7 it is at this time that the two slots 34 and 40 come 40 into alinement with each other and the suction therefore is completed from the exhausting apparatus to the tip of the duck-bill. This results therefore in effectively 45 getting hold of the thread and drawing it in. Then as the lay beats up and the slide is drawn back the duck-bill swings back and without any additional motion cuts off the 50 thread at the place where it passes through the two slots which now close past each other and shut off the suction.

The operation of the device has been 55 described and it will be understood that the parts are so timed by means of the cam 26 that the duck-bill on each side follows in to the shed immediately after the respective shuttle is thrown, first on one side and then 60 on the other, and each of them is drawn back again before the shuttle is thrown back from the other side. It is this double registering and turning motion that is responsible for securing efficient action for 65 the purpose intended, following up the broken thread as it were, and getting hold of it no matter how it may lie in the shed.

In order to adjust the device for narrower or wider cloth the brackets 21 and 31 and 65 cams 26 are loosened and, moved out or in,

and again fastened. This in itself will move the slides along to the proper position. The cams 46 then have to be adjusted similarly.

Although I have illustrated and described 70 only a single form of the invention I am aware of the fact that modifications can be made therein by any person skilled in the art without departing from the scope of the invention as expressed in the claims. Therefore 75 I do not wish to be limited to all the details of construction herein shown and described but what I do claim is:—

1. In a device for the purpose specified, the combination with the lay, of a guide located therealong, and means movable along the guide and guided thereby for entering the shed for the purpose of removing broken filling threads from the shed and adapted to move transversely also. 80

2. In a device for removing broken filling threads from the warp of a loom the combination with the lay and a guiding means extending longitudinally thereof across the loom, of a slide movable on said guiding 90 means at each end of the loom, and a suction device carried by each slide for removing the broken filling threads.

3. The combination with the lay of a loom, of a track carried by said lay and extending entirely across the loom, a pair of slides mounted to move on said track, and means for moving said slide in toward the center of the loom, timed to follow the inward motion of the shuttle from that end, 100 and for retracting it.

4. The combination with the lay of a loom, of a track carried by said lay, a pair of slides mounted to move on said track, means for moving each slide in toward the center of the loom after the shuttle moves in from that end, and for retracting it, a suction nozzle carried by the slide, and means for turning said nozzle after it moves into the shed. 110

5. In a device for removing broken filling threads from the warp of a loom, the combination with the lay and a track extending longitudinally thereof, of a slide movable on said track at each end of the loom, pneumatic means oscillatably carried by each slide for removing a broken thread from the shed, and means for swinging the pneumatic means as it moves into the shed. 115

6. In a device for removing broken filling threads from the shed of a loom, the combination with the lay, of a track secured thereon, pneumatic means movable along the track and guided thereby for entering the shed, and means whereby said means is 125 moved transversely with respect to the sliding motion of said means after it begins to move into the shed.

7. In a device for removing broken filling threads from the shed of a loom, the combi- 130

- nation with the lay, of a pneumatic nozzle carried thereby and capable of turning forward on a vertical axis to enter the shed and move close to the crossing warp threads.
- 5 8. The combination with the lay of a loom, of a movable suction nozzle, and means for controlling the motion of the suction nozzle to move it forwardly lengthwise of the cloth substantially into contact with 10 the crossing threads of the shed after the shuttle is thrown.
9. The combination with the lay of a loom, of a suction nozzle, means on the lay for guiding the suction nozzle, means for 15 controlling the motion of the suction nozzle to move it inwardly from the edge of the loom and then move it forwardly substantially into contact with the crossing threads of the shed after the shuttle is thrown.
- 20 10. In a device for removing broken threads from the shed of a loom, the combination of the lay, a guide extending along the lay, a slide movable on said guide, a cam timed to move the lay, means connected with 25 the cam for moving the slide inwardly toward the center of the loom as the lay is about to beat up after the shuttle is thrown.
11. In a device for removing broken threads from a loom shed, the combination 30 of a guide extending along the lay, a slide movable on said guide, a cam, means connected with the cam for moving the slide inwardly toward the center of the loom, a suction device mounted on said slide and com- 35 prising a tube and a suction nozzle oscillatably mounted on said tube, and means whereby when the slide moves in the nozzle will swing forwardly toward the crossing threads of the shed.
- 40 12. In a device for removing broken threads from a loom shed, the combination of a lay, a slide movable along said lay, a cam timed to move with the lay, means operated by the cam for moving the slide in- 45 wardly toward the center of the loom, a suction tube movable with said slide, a suction nozzle oscillatably mounted on said tube, means whereby when the slide moves in the nozzle will swing forwardly toward the 50 crossing threads of the shed, said tube and nozzle being provided with slots adapted to come into registration when the nozzle is turned forwardly and to move out of registration when the nozzle is moved back to 55 normal position.
13. In a device for removing broken threads from a loom shed, the combination of a lay, a suction device thereon, a cam
- timed to move with the lay, means connected with the cam for moving the suction device 60 out and in, said suction device comprising a stationary tube and a suction nozzle oscillatably mounted on said tube, means whereby when the suction device moves inwardly the nozzle will swing forwardly toward the 65 crossing threads of the shed, said tube and nozzle being provided with slots adapted to come into registration when the nozzle is turned forwardly and to move out of registration when the nozzle is moved back to 70 normal position, said slots having cutting edges for cutting the thread when the nozzle turns back.
14. In a device for removing broken threads from a loom shed, the combination 75 of a guide extending along the lay, a slide movable on said guide, a cam timed to move with the lay, means connected with the cam for moving the slide inwardly toward the center of the loom when the lay beats up 80 after the shuttle is thrown, a suction device mounted on said slide, a suction nozzle oscillatably mounted on said suction device, means whereby when the slide moves in the nozzle will swing forwardly toward the 85 crossing threads of the shed, the means for operating the slide being adjustable toward and from the center of the loom to provide for operation on cloth of different widths.
15. A filling thread removing device for a 90 loom comprising a suction nozzle of duck-bill shape mounted to swing on a vertical axis into the shed in the direction of the feed of the cloth.
16. A filling thread removing device for 95 a loom comprising a suction nozzle mounted to swing into the shed in the direction of the feed of the cloth.
17. A filling thread removing device for a loom comprising a suction nozzle mounted 100 to swing into the shed in the direction of the feed of the cloth, and means for adjusting the extent of its motion.
18. The combination with the lay of a loom, of a suction nozzle, means on the lay 105 for guiding the suction nozzle, means for controlling the motion of the suction nozzle to move it inwardly from the edge of the loom and then move it forwardly substantially into contact with the crossing threads 110 of the shed after the shuttle is thrown, and means for adjusting the extent of its motion.

In testimony whereof I have hereunto affixed my signature.

ROBERT J. ADAMS.

DISCLAIMER.

1,371,659.—*Robert J. Adams*, West Auburn, Mass. DEVICE FOR REMOVING BROKEN PICKS. Patent dated March 15, 1921. Disclaimer filed December 7, 1923, by the patentee.

Hereby enters this disclaimer—

“To claim 3 in said specification, which is in the following words, to wit:

“3. The combination with the lay of a loom, of a track carried by said lay and extending entirely across the loom, a pair of slides mounted to move on said track, and means for moving said slide in toward the center of the loom, timed to follow the inward motion of the shuttle from that end, and for retracting it.”
